FUEL SAVING DEVICE FOR INTERNAL COMBUSTION MOTORS

Enrique Nieves Bosdet, Mexico, D. F., Mexico

Application April 9, 1940, Serial No. 328,789
In Mexico November 16, 1939

2 Claims. (Cl. 48—180)

This invention relates to a fuel saving device for internal combustion motors, and more particularly to an addition to be added to the carburetor of said motors between the inlet of the detonating mixture coming out of the carburetor and this.

It is known that the operation of the internal combustion motors is based on the expansion of the gas produced by the ignition of the detonating mixture formed by the air and the gasoline, and that there is always a waste of gasoline owing to the incomplete mixture of this fuel with the air however much has already been obtained with the advancement of the modern carburetors.

The device subject of this invention has for its object to get a better mixture of the gasoline with the air after these elements have passed through the carburetor in the proper proportions.

The features of the device become apparent in the following description as well as in the attached drawing as an illustration of the former, the same reference figures serving to show the same parts in the four figures shown.

In the drawing:

Fig. 1 is a lateral view in elevation of the assembly that constitutes the present device.

Fig. 2 is a plan view of the same device in which more clearly appears the shape of the common joint or separator by means of which the device is set up between the inlet of the motor and the carburetor.

Fig. 3 is a sectional elevation view of the assembled device on a plan through the line A—B in Fig. 2. This figure is illustrated in enlarged size in order to show more accurately the interior parts thereof; the other three figures shown in a proportionate size.

Fig. 4 is a plan view of the same device, but showing its rear part.

Such as shown in the attached drawing, the device consists substantially of a cylindrical tubular housing 5, open at both ends, provided with a flange 6 integral with said housing as shown more clearly in Fig. 3 of the drawing, said flange has the shape the inlet of the carburetor generally has, that is, it extends laterally to each side and is provided in said extensions with the borings 7 through which the screwed bolt (not shown) passes and by means of which the device is attached between the inlet of the motor and the carburetor of the car.

Fixed by means of screws or rivets 8 to the side walls of said housing there are two diametral

bars 9 and 10 provided with two cylindrical tubular housings 11 and 12, located in opposite positions and in which are lodged the stubs or pivots 13 and 14, the housings 11 and 12 are provided with the ball bearings 17.

The axle 15 of the fan 16 is really constituted by the two tubular extensions of each one of the aforesaid pivots 13 and 14 in whose inside is lodged the springs 18 which tends to maintain them in constant contact against their respective ball bearings 17 in which they turn; furthermore, as already stated, it carries a fan 16 that turns with said stubs or pivots 13 and 14 by means of a small wing of the body 19 that enters a small groove practised longitudinally in said shaft.

The fan 16 can have a variable number of blades, and its dimensions as well as its separation of each other will be the most convenient according to the maximum amount of fuel that should pass into the motor.

In the lower portion of the tubular housing 5 and under the diametral lower bar 9, is located another tubular element 20 whose ends are closed by means of two metallic net discs 21. The lower end of said tubular element 20 is provided with a circumferential flange 22 that rests in a cutting made at lower end of the housing 5. A screw ring 23 presses against said flange 22 and keeps the element 20 in place under the diametral bar 9.

The ensemble of the device, constituted in the way described in the foregoing paragraphs, is closed through the cover 24 provided with a central perforation in which is inserted a cylindrical rod 25 with which the upper diametral bar is provided just in its center 10; besides, it is provided at its sides with the drill holes 26 which exactly coincide with those similarly practised in the flange 6 of the housing 5.

Once the cover 24 is placed on the flange 6 of housing 5, the ensemble located between the carburetor and the inlet for the gas into the motor is obviously understood.

The operation of the device is as follows:

The detonating mixture of gasoline and air that comes out of the carburetor by the suction produced by the cylinders of the motor at first passes through the free spaces, between the wings of the fan 16 which turns by the gas and air current through the carburetor and said current is blown by wings of the fan on turning which produces a better mixture of both elements fuel and combustion agent. The detonating mixture passes through the net 21 which

atomizes the mixture and makes it more intimate between the gasoline and the air, and therefore, a better utilization of the fuel and a saving in same therefore.

Having thus described the invention, what I consider as new and desire to secure by Letters Patent is:

1. In a fuel saving device, a casing open at each end, bars secured transversely of the casing in spaced relation and extending throughout the full diameter of the casing, a socket projecting from the proximate surfaces of the bar in the axial line of the casing, pivot members mounted for rotation in each socket and extending beyond the socket as tubular extensions which are aligned axially of the casing, a fan having

10 a central hub keyed on both said extensions to prevent independent rotative movement and permit free axial movement, a spring housed in the extensions and maintaining separating pressure on the respective pivot members, and an anti-friction element for the pivot member in each socket, the bearing contact between the pivot members and anti-friction elements being maintained by said spring.

15 2. A construction as defined in claim 1 together with a unit including a tubular section fitted removably in the end of the casing beyond one of said bars, and screens secured to the respective ends of the tubular section and extending transversely of the casing.

ENRIQUE NIEVES BOSDET.
